D8-335.

OR D12,891 EX

Apr. 18, 1882

UNITED STATES PATENT OFFICE.

THOMAS LYONS, OF HARTFORD, ASSIGNOR TO THE RUSSELL & ERWIN MANUFACTURING COMPANY, OF NEW BRITAIN, CONNECTICUT.

DESIGN FOR A PADLOCK.

SPECIFICATION forming part of Design No. 12,891, dated April 18, 1882.

Application filed March 2, 1882. Term of patent 14 years.

To all whom it may concern:

Be it known that I, THOMAS LYONS, of the city and county of Hartford, and State of Connecticut, have invented a new and Improved 5 Design for Padlocks; and I do hereby declare that the following specification, taken in connection with the accompanying illustration, forming a part of the same, is a full, clear, and exact description thereof.

10 The novel feature of the design hereinafter described consists in the configuration of the body of the padlock, representing two intersecting cylinders of unequal diameters.

As shown in the illustration, the contour of 15 the face of the lock is in the form of a circle, A, which is intersected externally by a smaller circle, B—that is, the face of the lock resembles two intersecting disks arranged in the same

plane and of unequal diameters. Preferably the key-hole of the lock is located within the 20 periphery of the smaller circle B, and the surface, bounded by the larger circle A, is ornamented by floral decorations or in any preferred manner, or may be unornamented, as desired.

As shown in the illustration, the periphery 25 of the face of the lock is ornamented by a molding; but such molding may be dispensed with and the edge be left plain.

What I claim, and desire to secure by Letters Patent, is—

30 The design for a padlock, substantially as herein described and shown.

THOMAS LYONS.
